Inventor.

Charles Brooker
by Chas. A. Neill ATTORNEY

ATTORNEY

UNITED STATES PATENT OFFICE.

CHARLES CROZIER, OF HONOLULU, TERRITORY OF HAWAII.

SLING.

Application filed April 17, 1922. Serial No. 553,475.

To all whom it may concern:

Be it known that I, CHARLES CROZIER, a citizen of the United States, residing at Honolulu, in the Territory of Hawaii, have invented certain new and useful Improvements in Slings; and I do hereby declare the following to be a full, clear, and exact description of the invention, such as will enable others skilled in the art to which it appertains to make and use the same.

The invention relates to a simple and efficient form of sling for binding and transporting loads or bundles of loose material, comprising a pair of cross-bars pivoted together intermediate their ends, and constituting a scissors-like frame, each of said bars having a guide means at one end, preferably provided with a sheave or guide roller mounted therein, and a flexible loop passing through said guide means having its opposite end attached to the opposite ends of the cross-bars, and flexible suspension means connecting said opposite bar ends, which tend to move the scissors frame to closed position, when the load is surrounded by the flexible loop and a lifting force applied to the sling, whereby the load is securely bound between the flexible loop and the closing bars of the frame, the binding force applied to the load being proportionate to the weight of the latter:

In the accompanying drawings,

Fig. 1 is an elevation of the sling before the load is applied;

Fig. 2 is a similar view showing the sling and applied load;

Fig. 3 is a plan view of the scissors-like frame of the sling;

Fig. 4 is a perspective view of one of the cross-bars of the frame.

Referring to the drawings, 1 and 2 are two cross-bars pivoted together intermediate their ends, by a bolt or pintle 3, so that said bars constitute a scissors-like frame capable of being moved to fully open position, as illustrated in Fig. 1, and to partially closed position as shown in Fig. 2. Each of said bars is provided at one end with a guide opening or slot 4 in the outer end of which is mounted a guide sheave or roller 5, a shoulder 6 to engage the lower edge of the co-operating bar and limit the opening movement of the frame, and a perforated lug 9 on the end opposite that carrying the sheave 5. Preferably the end of

each bar adjacent the lug 9 is provided with a pin-like extension 10.

The ends of the bars 1 and 2 are connected through the perforated lugs 9 by a flexible suspension device which, as illustrated, comprises two chain sections 15 with an intermediate suspension ring 14. A flexible connection 13 is interposed between the ring 14 and a bail 12, secured to the pivot 3 of the frame, and serves to limit the closing movement of the frame when the load is applied.

A flexible loop, consisting of a chain or cable, preferably formed with two sections united by a releasable latch or coupling, 70 has one end secured to a bolt 20 mounted near the end of the bars 2, said loop passing through the guide openings 4 in the ends of the bars 1 and 2, thence over a similar bolt 20 on bar 1, the free end of the flexible loop being suitably secured to the upper end of bar 1, as for example, by taking a half turn around the pin 10 on the end of bar 1, and passing between locking pins or lugs 29 and 30 on the side of bar 1. As illustrated in the drawings, the flexible loop comprises a chain section 21, and a connected rope or cable section 27, the chain section having interposed therein a releasable latch comprising a member 23 having a slot 24 therein into which is slipped a link member 22 on the end of one chain section, said member 23 being eccentrically pivoted at 26 in a yoke member 25 secured to the end of the other chain section. The member 23 is provided with a trip cord or rope, whereby said member is swung on the pivot 26 to release the link 22 from the slotted jaw 24.

It will be noted that the two bars of the frame are homologous and interchangeable and that the flexible loop of the sling may have its permanent attachment to either of the bars, on the corresponding bolt or stud 20. Obviously, if desired, both ends of the flexible loop may be detachably connected to the corresponding bar end.

In applying and operating the sling, the material to be bundled and transported thereby is assembled in suitable piles, each pile constituting a load for the sling. The scissors-like frame is locked in open position by passing a pin through registering holes 8 in the bars, and the frame is then laid cross-wise of the pile. The sections of

the flexible loop being disconnected at the latch, one of the loop sections is passed under the pile and the two loop sections joined together by the latch device. The locking pin is then withdrawn from the holes 8 and the sling is raised by a suitable lifting device connected to the ring 14. The lifting force applied to the sling and resisted by the load causes the two bars of the frame 5 to swing on their pivot 3, like the closing movement of a pair of scissors, until such movement is arrested by the conjoint action of the flexible connections 15 and 13. The relative movement of the two bars 1 and 2 10 causes the sheaves 5, 5, on the ends thereof to engage the flexible loop surrounding the load, and, as the sheave ends of the bars move downward, the slack in the flexible loop is taken up and the latter is drawn 15 taut about the load, as indicated in Fig. 2, so that the load is firmly clamped between the ends of the frame and the flexible loop, and may be safely transported to the place 20 of final disposition without danger of any of the elements of the load working loose. To discharge the load, it is only necessary 25 to release the latch mechanism connecting the sections of the flexible loop. The scissors frame of the sling is then again moved 30 to open position and the bars 1 and 2 locked in this relation by passing a pin through one or the other sets of registering openings 8 in said bars.

It will be understood that the guide slots 35 and sheaves in the lower ends of the bars, while constituting the preferred construction, are merely exemplary, and may be substituted by any other suitable form of confining guide means associated with the lower 40 ends of the bars, through which the flexible loop passes. It will also be obvious that any other suitable means for securing

the free ends of the flexible loops to the upper ends of the bars may be employed.

What I claim is:

1. A sling comprising cross-bars pivoted together intermediate their ends, a flexible loop having its ends attached to the upper ends of the respective bars and its intermediate portion passing through confining guides on the lower ends of said bars, and suspending means connecting the upper ends of said bars. 45

2. A sling comprising cross-bars pivoted together intermediate their ends, a flexible loop having its ends attached to the upper ends of the respective bars, and its intermediate portion passing through confining guides on the lower ends of said bars, flexible suspending means connecting the upper ends 50 of said bars, and a flexible tie between the middle of said suspending means and the pivotal axis of said bars. 60

3. A sling comprising cross-bars pivoted together intermediate their ends, each having a guide opening at its lower end, a flexible loop passing through said guide openings and having its ends attached to the upper ends of the cross-bars, and flexible suspending means connecting the upper ends 65 of said bars. 70

4. A sling comprising cross-bars pivoted together intermediate their ends, each having a guide opening at its lower end and a roller in said opening, a flexible loop passing through said guide openings and having its ends attached to the upper ends of the cross-bars, and flexible suspending means connecting the upper ends of said bars. 75 80

In testimony whereof I affix my signature.

CHARLES CROZIER.
